CLOTHESLINE ATTACHMENT

Charles H. Reske, San Francisco, Calif.

Application April 11, 1933. Serial No. 665,574

1 Claim. (Cl. 68—3)

This invention relates to improvements in clothes line attachments and has particular reference to a means for securing clothes or other objects to a clothes line.

5 The principal object of the invention is to provide means on a clothes line for gripping the clothes thereon, and entirely eliminating the use of the conventional clothes pins.

A further object is to produce an attachment 10 which is not harmful to the clothes being held and one wherein the gripping action may be readily accomplished.

A further object is to construct a clothes line 15 with clamping means so positioned therein, that the travel of the line over the supporting pulleys will, in no way, be interfered with or retarded.

A still further object is to produce a device which is economical to manufacture.

Other objects and advantages will be apparent 20 during the course of the following description.

In the accompanying drawing forming a part of this specification and in which like numerals are employed to designate like parts throughout the same,

25 Fig. 1 is a side elevation of a pulley line having my invention applied thereto,

Fig. 2 is a top plan view of Fig. 1,

Fig. 3 is an enlarged fragmentary detail view,

Fig. 4 is a cross sectional view on the line 4—4

30 of Fig. 3, and Fig. 5 is an enlarged cross sectional view on the line 5—5 of Fig. 3.

Clothes are usually attached to clothes lines through the medium of a fastening element such 35 as a clothes pin. Applicant has devised a simple and unique medium for securing clothes to the clothes line, entirely eliminating the use of pins, which are objectionable because they are often dropped and lost, easily become broken and are 40 difficult to handle. Applicant proposes to use a double line, with a plurality of fixed clamps holding the two lines parallel with each other, and by providing a plurality of sliding clamps upon the lines, a gripping action is effective that retains 45 the goods placed between the lines.

In the accompanying drawing wherein for the purpose of illustration is shown a preferred embodiment of my invention, the numeral 5 designates an ordinary pulley wheel as does also the numeral 6. Reeved over these pulley wheels is 60 a clothes line which consists of strands 7 and 8. It will be noted that the top portion of the line consists of a single strand 10, while the bottom portion, as before mentioned, consists of the double strands 7 and 8. These strands are parallel 65 with each other, which permits a series of clamps 9 to be secured thereto. A series of sliding clamps 11 are movable upon the lines as indicated by the arrows in Fig. 3. It is, of course, understood that as many of these clamps may be placed upon the 70 line, as the length of the line will permit in order to accommodate for goods or garments of various sizes.

The manner of using my device is as follows: If it is desired to clamp a piece of material be- 75 tween the lines, one of the clamps 11 is slid for instance, toward the right of the drawing. The two strands 7 and 8 are then separated, and a portion of the goods placed therebetween. The clamp 11 is thereafter moved back toward the 80 left of the drawing, thus effecting a gripping of the goods as illustrated in Fig. 1.

It is to be understood that the form of my invention herewith shown and described is to be taken as a preferred example of the same and 85 that various changes relative to the material, size, shape and arrangement of parts may be resorted to without departing from the spirit of the invention or the scope of the subjoined claim.

Having thus described my invention, I claim:— 90

The combination with a pair of pulley wheels, of an endless clothes line reeved thereover, said line embodying in its construction a single strand portion and a double strand portion, secured one to the other, and means carried by said double 95 strand portion for retaining therebetween articles to be hung, said means including a fixed element and a sliding element.

CHARLES H. RESKE.
